UNITED STATES PATENT OFFICE.

HOUGHTON WARDELLE WILSON, OF KINGSTON, ONTARIO, CANADA.

DESIGN FOR A PACKING-CASE.

SPECIFICATION forming part of Design No. 14,896, dated March 18, 1884.

Application filed August 28, 1883. Term of patent 14 years.

To all whom it may concern:

Be it known that I, HOUGHTON W. WILSON, a citizen of the Dominion of Canada, residing at Kingston, in the county of Frontenac, Province of Ontario, Dominion of Canada, have invented a new and useful Design for a Package Case or Envelope, of which the following is a specification, reference being had to the accompanying drawing.

10 The annexed drawing shows an isometrical projection of my newly-designed package case, holder, or envelope.

The leading features of my design consist in a package-case, or holder, or envelope, 15 triangular in shape, with ornamental borders and ornamental small triangles within the border.

16 A is the package case, or holder, or envelope, which is triangular in configuration, having 20 an upper and underside, b and b' , and end b^2 , as

shown in the drawing. The front and rear sides of the package are ornamented with border-lines and small triangles at the corners, as shown.

I claim—

1. A design for a package case or envelope, triangular in shape, and ornamented with border-lines, as shown. 25

2. A design for a package case or envelope, triangular in shape, the sides being flat and 30 ornamented with border-lines and small triangles, as shown.

In testimony that I claim the foregoing as my own I have hereto affixed my signature in presence of two witnesses.

HOUGHTON WARDELLE WILSON.
